UNITED STATES PATENT OFFICE.

WILLIAM H. SHERIDAN, OF PITTSFIELD, MASSACHUSETTS.

KNITTING-MACHINE.

SPECIFICATION forming part of Letters Patent No. 699,930, dated May 13, 1902.

Application filed June 11, 1901. Serial No. 64,165. (No model.)

To all whom it may concern:

Be it known that I, WILLIAM H. SHERIDAN, a citizen of the United States, residing at Pittsfield, in the county of Berkshire and State of Massachusetts, have invented an Improvement in Knitting-Machines, of which the following description, in connection with the accompanying drawings, is a specification, like characters on the drawings representing like parts.

In machines employing two sets of spring-needles for knitting ribbed fabric it is customary to employ two knock-off bars, one bar for each set of needles, the bar for the series of horizontal needles occupying a stationary position, while the bar coacting with the vertical needles is moved so that it acts to knock the loops off the vertical needles while the hooked ends of the horizontal needles occupy a position in front of the series of vertical needles, or, in other words, the loops are knocked off the vertical needles while the loop of the fabric held on the horizontal needles lies on the shanks of said needles near the points of their beards. In this old form of machine much difficulty is experienced in using heavy yarn or yarn unevenly spun, as well as slack-twisted-yarn.

My invention has for its object to improve this well-known class of knitting-machine, so that any yarn, either heavy-weight or unevenly-spun or slack-twisted yarns, may be employed in the knitting of a ribbed fabric, as well as the finer, even, and hard-twisted, 35 yarns. To accomplish this purpose, I have provided means whereby the needle-bar carrying the horizontal needles and occupying a position with their points at the rear side of said vertical needles is moved forward or toward said vertical needles for a distance sufficient only to slacken the strain on the loops then held between the two sets of needles, and the tension on the loops held by the needles having been somewhat relaxed 45 the horizontal needles are held substantially stationary with their front ends behind the vertical needles while the knock-off bar co-operating with the vertical needles is raised to knock the loop off the upper ends of the vertical needles, and this done the horizontal needles are moved forwardly for their full stroke through the loops then held on their

shanks, said needles receiving yarn for the formation of new loops, and the vertical needles, the knitted loops having been cast off 55 their tops in the meantime, are raised above the horizontal needles that yarn may be fed to the horizontal needles, the latter during their movement rearwardly drawing the yarn through the loops on their shanks and laying 60 the yarn held by them across the shanks of the vertical needles, so that the latter when they descend may take the thread, form it into loops which are drawn through the loops then on the shanks of the vertical needles. 65

In my invention the knock-off bar for the vertical needles when in its elevated operative position occupies a position in and preferably slightly above the plane in which the horizontal needles move, and said bar has a 70 continuous upward movement into said position until the stitches are cast off, said vertical needles at such time also descending.

Figure 1 is a sectional detail of a sufficient portion of a well-known knitting-machine 75 with my improvements added to enable my invention to be understood. Figs. 2 and 3 are details of newly-devised cams to enable my machine to be operated in accordance with my invention. Figs. 4 to 10 are views 80 showing the parts in the positions they will occupy in knitting a ribbed fabric in accordance with my invention.

My invention is applicable to any well-known knitting-machine using horizontal and 85 vertical or crossing needles of the bearded class. An early form of machines of this class is represented in United States Patent No. 28,133, dated May 1, 1860.

Referring to Fig. 1, A represents part of 90 the framework; A¹, a cam-shaft; A', a needle-bar suitably connected with a slide A² and carrying a series of horizontal needles a of the bearded variety. B is a lever pivoted loosely on a shaft B' and engaging a stud a³ 95 on and to draw the needle-bar to the right, a spring B² acting, when permitted to do so, to move said needle-bar forward. B³ is a knock-off bar coacting with the loops hanging on the horizontal needles. C is a needle-bar carrying the vertical needles c. These parts may be the same as the like-named parts in said patent. The needles will be supplied with 100 yarn, and each set of needles in practice will

have coöperating with it suitable beard-closers, as shown in said patent or as usual in the class of machine using two sets of bearded or crossing needles, and the horizontal needles will have coacting with them usual sinkers to act on the yarn and sink it between the horizontal needles. The knock-off bar D is employed to knock the usual loops on the vertical needles over the heads of said needles and to even and set the stitch.

The invention herein to be described relates more particularly to actuating the horizontal needles and the knock-off bar D in such a manner as to reduce the strain on the thread being knitted, so that knitting may be done with large yarns, yarns not evenly spun, and also slack-twisted yarns without the liability of their being broken.

The cam-shaft A^x is provided with a cam b, which acts upon and moves the lever B, said cam controlling the movement of the bar carrying the horizontal needles. This cam in accordance with my invention has a face b', which may be adjusted on the body of the cam to provide a space in which the roller of the lever for moving the needle-bar may enter, and thereby enable the horizontal needles to be started forwardly a little sooner than though the curved end of the cam was a true circle, thus stopping momentarily the forward movement of said needles, this slight forward movement and rest of the horizontal needles enabling the loops crossing from one to the other set of needles to be slackened just as the knock-off bar coacting with the vertical needles acts to knock off from said needles the loops then on their shanks, and said loops having been knocked off the horizontal needles are again started forwardly and are moved to the extent of their forward stroke. The face b' has a wing b², provided with a slot b³, entered by a set-screw b⁴ by which to clamp the face in its adjusted position to leave more or less of a recess, as b⁵, to permit a slight forward movement of the horizontal needles while the knock-off bar D for the vertical needles is raised, as will be described, in front of the horizontal needles to cast the loops on the vertical needles over their upper ends. It is necessary with different yarns to vary the extent of this preliminary forward movement given to the horizontal needles, and to do this accurately and positively I have provided means for adjusting the said wing b², said means, as shown, consisting of a screw 4 and an abutment 5, against which the screw rests.

The knock-over bar D for the vertical needles derives its movement from a cam d, having usual throw-points 6 7 and in accordance with my invention an additional throw-point 8, the latter point 8 acting in advance of the points 6 and 7 to move said bar upwardly farther than ever before provided for in machines of this class just after starting the horizontal needles forward to slacken the loops then held stretched from one to the other set of needles, the upward movement of said

knock-off bar taking place while the forward movement of the horizontal needles, the loops having been slackened, as stated, is substantially suspended, the upper edge of said knock-over bar coming into a position up to or above the plane in which the lower sides of the horizontal needles reciprocate.

The usual throw-points 6 and 7 act in succession to cause the knock-over bar D to rise and contact with the loops of the knitted fabric and by contact therewith even and set to shape the stitches.

The knock-over bar D, guided in its vertical movements in usual manner, has connected with it near each end a suitable arm D², surrounding loosely the shaft B', said arm being provided with a suitable roller or other stud D⁴, resting on the periphery of the cam. The levers B and D² and their actuating-cams are duplicated at each end of the machine.

In accordance with my invention and in practicing my new method of knitting I supply the horizontal needles a with yarn in the position Fig. 4, sink the yarn in usual manner between said needles, and draw the horizontal needles fully back, as represented in Fig. 5, closing their beards and drawing new loops of yarn through the loops then surrounding the shanks of said needles, the knock-over bar B³ serving to knock the loop on said needles from their ends over the closed beards, and the vertical needles are lowered, as in Fig. 6. When the horizontal needles are in their rearward position, Fig. 5, that portion of the circular part 11 of the cam b contacts with and holds the needle-bar A' back. In the continued movement of the cam b in the direction of the arrow thereon the recess 12, following the circular part 11, said recess being more or less in extent, according to the adjustment of the face b', arrives in contact with the said lever B and immediately the spring B² acts and starts the needle-bar A' forwardly into the position Fig. 6, and while the end of the face b' acts on said lever the needle-bar A' is substantially stopped in its forward motion, such slight preliminary forward movement of said needle-bar resulting in slackening or reducing the strain on the loop extended from one to the other set of needles. This preliminary forward movement and substantial rest of the horizontal needles is broadly new with me. With the needles in the condition Fig. 6, the knock-over bar D has imparted to it the novel movement herein provided for—i. e., the point 8 for the first time used by me acts to lift the knock-over bar and put its edge into the plane of or above the plane of movement of the horizontal needles, so that said knock-over bar acts against the loops of yarn extending from one to the other set of needles and knocks over the loop on the vertical needles while the tension is relaxed.

Fig. 7 shows the knock-over bar slightly depressed and the horizontal needles advancing in the next step in knitting, while Figs.

8, 9, and 10, respectively, show the relation of the vertical and horizontal needles and knock-over bar in completing a cycle of movements in the knitting operation.

5 I believe that it is new to slacken the loops held extended between the horizontal and vertical needles and while so slackened to lift the knock-over bar coacting with the vertical needles to knock the loops next to be 10 discharged over the upper ends of said needles, and I desire to claim this feature, broadly, independently of the particular mechanical means employed to impart to said horizontal needle-bar and the knock-over bar 15 D their new movements to thereby improve the machine and the knitting.

Having described my invention, what I claim, and desire to secure by Letters Patent, is—

20 1. In a straight-knitting machine for knitting ribbed work, a set of substantially horizontal and a set of substantially vertical bearded needles, means to actuate the vertical needles, means to impart a preliminary forward movement to said horizontal needles and then substantially arrest them with their free ends back of the rear sides of the vertical needles to thereby sufficiently slacken the tension on the loops held by both sets of said needles, a 25 knock-off bar, and means to actuate it while the horizontal needles are substantially arrested to meet and knock over from the shanks of the vertical needles the loops next to be cast off in the knitting.

30 2. In a straight-knitting machine for knitting ribbed work, two sets of bearded needles, one set being arranged substantially vertical and the other substantially horizontal, means to actuate the vertical needles, means to impart a preliminary forward movement to said horizontal needles and then substantially arrest them with the ends of the hooks back of the rear sides of the vertical needles to thereby slacken the tension on the loops held by both

sets of said needles, a knock-off bar, and means to actuate it while the horizontal needles are in position to slacken the loops putting the acting edge of said knock-off bar in or above the plane of movement of the under sides of the horizontal needles.

3. In a machine of the class described, a series of vertical needles, means to actuate them, a needle-bar having an attached series of horizontal needles, means for moving said horizontal needles forwardly, actuating-levers 55 coacting with the bar carrying said horizontal needles, and a cam having a depression to enable the bar carrying said horizontal needles to partake of a preliminary forward movement and then arrest said bar with the ends 60 of the horizontal needles near the rear sides of the vertical needles, to thereby slacken the tension on the loops extended from one to the other set of said needles preparatory to knocking off the loops held on the shanks of 65 the vertical needles.

4. In a machine of the class described, a series of vertical needles, means to actuate them, a knock-off bar coacting with the vertical needles, means to actuate said knock-off 70 bar, a needle-bar having an attached series of horizontal needles, actuating-levers for said bar, and a cam having an adjustable face whereby a period of substantial rest may be given to the horizontal needles in their forward movement, to thereby slacken the tension on the loops extended from one to the other set of said needles preparatory to knocking off the loops held on the shanks of the 75 vertical needles.

In testimony whereof I have signed my name to this specification in the presence of two subscribing witnesses.

WILLIAM H. SHERIDAN.
